UNITED STATES PATENT OFFICE.

BENJAMIN F. CARPENTER, OF SUMMIT, NEW JERSEY.

EXTENSION-LADDER WITH RESCUE-CAR.

1,106,698.

Specification of Letters Patent.

Patented Aug. 11, 1914.

Application filed July 21, 1913. Serial No. 780,119.

To all whom it may concern:

Be it known that I, BENJAMIN F. CARPENTER, a citizen of the United States, residing at 22 Elm street, Summit, county of Union, and State of New Jersey, have invented certain new and useful Improvements in Extension-Ladders with Rescue-Cars, fully described and represented in the following specification and the accompanying drawings forming a part of the same.

This invention relates to an extension-ladder with a rescue-car movable upon the same, the ladder being pivoted upon a turn-table mounted upon a truck for transporting the ladder to any place. This structure requires other attachments to adapt the car for most efficiently rescuing persons and property from dangerous or elevated positions, for use in extinguishing fires, for 10 pairing high structures, and bridging impassable chasms and streams, for trimming and spraying high trees, for making observations in an elevated position, and performing other difficult work.

The object of the invention is to operate a car upon such a ladder in the most efficient manner, and such efficient operation requires a main-ladder with means for pointing it in any direction around the horizon and elevating it to any point from a horizontal to a vertical position. An extension-ladder is required for elevating the car to higher points than could be reached by a single ladder conveniently movable through the streets, and ropes and drums are required for projecting and retracting the extension-ladder and operating the rescue-car. Means is required for operating the turn-table by hand, to turn the ladders promptly into any position, and gearing is required operable by hand to elevate and lower the ladders with the car thereon, so as to avoid the use of ropes and drums for such purpose. An adjustable counterweight is required to 20 maintain the balance of the main and extension-ladders and the car thereon in any adjustment; as the movement of such car could not otherwise be controlled by hand-gearing. The adjustment of the counterweight cannot be effected without automatic means to indicate whether it requires to be moved toward or from the fulcrum of the ladder, and an index-finger giving such indication therefore enables the ladders to be balanced most efficiently. The counterweight must be attached to the lower end.

of the ladder by reversely bent arms or frames adapted to extend over and under the turntable at its opposite sides; so that the ladder may be balanced in all positions from the vertical to a horizontal, or even below a horizontal position. The ladders and car may also operate more efficiently if an underslung platform be provided to extend from any part of the building to rescue persons therefrom, and the ladder requires removable rungs at such point to permit the passage of persons from the underslung platform through the ladder to the car.

The car may operate to rescue persons beyond the reach of the extension-ladder, by means of an emergency ladder having its rails fitted to sockets in the car and projected upward therefrom, and such emergency ladder is enabled to be projected upward in contact with the wall of a building by providing the upper end of the same with a spring-guide-frame and a cushioned wheel at the forward end of the same to rest upon the building. The omission of any of these elements obviously deprives the structure of more or less of its efficiency.

A ladder is commonly made extensible by fitting the side-rails or frame of the extension-ladder inside the side-rails of the main ladder, that is, between the side-rails of the main ladder. In the construction shown herein, the inner sides of the rails of both ladders are grooved, and the bottom of the car fits loosely between the rails and is furnished with latches to engage the grooves, to retain the car upon the ladder when moved thereon. The car is provided with wheels or rolls at opposite sides having tread broad enough to rest upon the upper surface of the ladder-rails of the main and extension-ladders, and the car is provided with guide-ribs which are adapted to fit inside the rails of the main ladder and outside the rails of the extension-ladder. The latches are movable laterally upon the bottom of the car and pressed outwardly into the grooves of the ladder by suitable springs. The grooves in the rails of the extension-ladder are curved downwardly and outwardly at the foot of such ladder so as to coincide with the grooves in the rails of the main-ladder, so that when the latches upon the bottom of the car move from the grooves in the main ladder to the grooves in the extension-ladder, they may be guided automatically from one to the other, being

pressed inwardly in opposition to the springs during such movement. When the car is descending upon the ladder the rolls are held from revolving by ratchets having 5 detachable pawls and the rolls or wheels then act as shoes to slide upon the rails. The supports of the guide-ribs upon the car also constitute bearing plates adapted to support the car in case a wheel be broken. The 10 latches may be wholly retracted from the grooves to remove the car from the ladder when desired.

The car is operated by a rope extending over a pulley fixed upon the upper end of 15 the extension-ladder downwardly along the under side of the ladders, and over a pulley or pulleys arranged and supported on the turntable, to hoisting drums located at any convenient point upon the truck. Such 20 drums may be operated by hand or power, as preferred.

An emergency or auxiliary ladder may be used to extend the means for reaching objects or persons beyond the top of the extension-ladder, the lower end of such emergency ladder being supported upon the car in such manner that it may swing freely to and from a building as it is elevated, and it is held from lateral movement by the sides 30 of the car-railing. Its upper end is provided with a leading or guide wheel supported on a spring-pressed guide-frame which has curved runners adapted to slide over lintels, sills or other obstructions upon 35 the face of a building, and also form a bridge-support for the guide-wheel in its movement over open windows or other breaks in the continuity of the wall.

The emergency ladder is provided with 40 lugs or brackets to rest upon the rungs of any ladder, and also has means for hooking it upon a window-sill so that it can be left there for a time while a load of rescued persons is being carried to the ground in the 45 rescue-car.

To facilitate the swinging of the main ladder from a horizontal to a perpendicular position and to furnish a counterbalance opposed to the weight of the main and extension-ladders in any position of such ladders, I connect the main ladder with the counterbalance by a metallic frame of S-shape which extends over and under the turntable at its opposite sides as herein- 50 after described. The counterbalance-weight 55 is attached to such frame by telescoping frames which are movable to and from the fulcrum of the main ladder and serve to vary the position of the weight, as may be 60 required to balance the load upon the ladders.

When the extension-ladder is projected laterally from the main ladder the length may be sufficient in many cases to use as a 65 horizontal or inclined bridge over a stream,

a depression in the ground, or a gap in a building, and as the strain upon the ladders is much increased by loading them in a horizontal position, I prefer to support such bridge by an additional ladder selected to 70 operate as a post or leg beneath the middle portion of the bridge, one of the bridge-ladders being furnished with an eye, and such supporting ladder furnished with a hook to engage the same and hold it in position 75 while resting upon the ground beneath the bridge.

The extension-ladder is furnished with the required strength by making it with double rails at each side, the outer rails lying outside the rails of the main ladder so that they may be trussed with top and bottom chords. Such outer rail may also supply a 80 constant support for the foot of the extension-ladder, by providing such outer rail with a rigid hook or under-shoe to move beneath the rail of the main ladder, the inner rails of the extension ladder also carrying 85 at the lower ends lugs or shoes to slide in the grooves of the main ladder rails and thus furnish additional support to brace the extension-ladder when projected.

All the ends of the ladders are preferably 90 constructed with steel casings or shoes to properly support and strengthen them and resist the strains to which they are subjected. Such steel ends when the extension-ladder is fully projected, are combined with means for locking the rails together so as to 95 join them with sufficient strength for all the 100 normal uses of the apparatus. Detents are also provided upon each of the rails of the main ladder at their upper ends to engage 105 pockets in the rails of the extension-ladder, so that when it is brought to rest they relieve the strain upon the hoisting-rope and make the support trebly safe.

A detachable platform termed an "undersling" herein, is constructed to sling beneath any part of the main or extension-ladders 110 when inclined against the front of a building and supplies a means of access between the building and a rescue-car at intermediate stories below the ladder's end, and is so supported as to allow the car to pass. Certain of the 115 rungs in the ladder are made removable, to facilitate the egress of the persons from the platform through the ladder to the outer side of the same or to the car. Such undersling platform is so constructed that it may 120 be readily applied to and removed from any of the rungs upon the ladder, and furnishes an adjustable scaffold for any required purpose; and where the apparatus is used 125 chiefly in fighting fire, the extension-ladder may be constructed at suitable intervals with the detachable rungs described herein, which permit access to the ladder at various points.

The invention will be understood by reference to the annexed drawing, Figure 1 being 130

a diagram showing the relation of the main ladder, extension-ladder, emergency ladder, and car to a building; Fig. 2 shows the upper end of the extension-ladder with the emergency ladder hooked upon a window-sill above it; Fig. 3 is a side elevation of such truck and apparatus arranged for transportation through the streets the counterbalance of the ladders being omitted 5 for want of room upon the drawing; Fig. 4 is a plan of the same; Fig. 5 is an elevation of the apparatus with the ladders erected in front of a building; Fig. 6 shows upon a larger scale than Fig. 5 the connection 10 of the ladders, and the ropes for operating the same and the car; Fig. 7 is a plan of the undersling platform upon a larger scale than appears in Fig. 5; Fig. 8 is a plan of the turntable and the lower end of the 15 main ladder with its connections thereto; Fig. 9 is a side-view of the same parts with the turntable in section; Fig. 10 is an end view at the middle of the turntable, of the main ladder connections thereto, the view 20 being drawn upon a larger scale than Fig. 9; Fig. 10^a is a plan of a portion of the rails of the extension-ladder where a detachable rung is connected thereto; Fig. 10^b is a cross-section of the rails through the center 25 of the detachable rung; and Fig. 10^c is a horizontal section through the end of the detachable rung. Fig. 11 is a side elevation of the car and the inner side of the rails of the main and extension-ladders at their 30 junction; Fig. 12 is a plan of the same parts with the hand-rails upon the car omitted at one side thereof; Fig. 13 is a cross-section through the center of the bearing-roller at the right hand end of the car in Fig. 12, 35 with the rear or foot of the extension-ladder; Fig. 14 is an elevation of the rear end of the car omitting one bearing-roll; Fig. 15 is a plan of the main and extension-ladders at their junction, with the contiguous ends 40 of the rails in section where hatched; Fig. 16 shows the rear side of the spring guide frame upon the upper end of the emergency ladder; Fig. 17 is a section on line 17—17 in Fig. 16 with such carriage hooked upon 45 the window-sill of a building; Fig. 18 is a plan of the telescoping slides for the counterweight upon the main ladder; Fig. 19 is a section on line 19—19 in Fig. 18; and Fig. 50 55 20 is a cross-section on line 20—20 in Fig. 18; Fig. 21 is an elevation, and Fig. 22 a plan of the connection between the pusher-rack *f'* and the counterbalance frame of the ladders.

The truck shown in Figs. 3 and 4 consists of side-frames having level ends *a*, *a'* connected by an arch formed with sloping sides *b*, *b'*. The sides and top of the arch are trussed by beams *a²* suitably braced. The side-frames are connected by cross-bars 60 *a³* and diagonal braces, and the arches of

the frames are trussed by a central tie-bar or "reach" *b²*, which connects the ends of the truck across the middle of the arch, and is held as near the ground as is practicable by struts *c²* projected downward from the 70 tie-beams *a³* nearest the base of the arch. Wheels *A* and *A'* are shown under the ends of the truck, and hand-wheels *B* and *B'* are shown upon the truck-frame for steering. Such a truck may be propelled by any desired means, and if a gasolene motor or storage battery motor be provided the same power may be used for hoisting and operating the ladders and the rescue-car. The 75 turntable *e* is mounted upon an annular seat *f* at the tops of the arches; and the main ladder *C* is pivoted to the turntable by a shaft *e²* and pivot-bearings *e'* at opposite sides of a gap *g*, through which the pivot-frame *C'* of such ladder can swing downwardly. Such pivot-frame carries the counterbalance-weight *C²* mounted upon the telescoping frames *C³*, *C⁴* and *C⁵*, shown in Figs. 18 to 20 inclusive.

The letter *C* is applied in Fig. 8 to the side-rails of the main ladder, which are connected by rungs *c* and provided along their inner edges with the grooves *c'*, same frame *C'* is of metal plates connected by a tie-bar, and each plate is of S-shape formed with 90 reflex bends, having a body extended laterally at opposite sides of the pivot-bar *e²* and formed with one arm extended above the turntable, to which arms the ladder-rails *C* are attached. An opposite or rear arm 95 extends through the gap *g* beneath the turntable, and is bent, beyond its edge, to the line of the said rails *C*, and the frame-bars *C⁵* for the counterweight are attached to such rear arm. By this construction the counterweight moves below the pivotal support 100 when the ladder moves above said support, and without interference of the turntable in any position of the ladder thereon.

By its S-shape, the frame *C'* is enabled to 110 sustain a counterweight upon the side of the pivot-shaft *e²* opposite the center of gravity of the combined main and extension-ladders, and permits all the necessary movements of the ladder from an elevated 115 to a depressed position without the necessity of forming any opening or gate in the side of the turntable or its supporting ring. The metal frame *C'* is preferably formed with arms *C⁶* bent downward from the junction 120 of the rails *C* with such frame, to form a foot for a truss-bar *C⁷* which is trussed to the main rails *C* by diagonal braces *C⁸*, thus greatly increasing the strength and stiffness of the main ladder. The arm *C⁶* gives the 125 entire metal ladder-frame an S-form, as is apparent in Fig. 9, which form is claimed herein.

The frame *C'* is tipped to elevate or depress the ladders by connections to a hand- 130

wheel l^3 , a shaft g' extending downward from the hand-wheel to gearing connected with a rack-bar f' , the end of which is connected removably to a cross-bar f^2 at the rear end of the frames C' . The rack-bar is held in contact with a pinion h' of the gearing by a hinged yoke h^2 , which is adapted to swing around the shaft h^4 of the pinion as the rack-bar changes its angle during the swinging of the frames C' upon their pivot-bar c^2 . The gearing is proportioned to diminish the speed and increase the power applied by the operator to the hand-wheel l^3 , which enables the operator to tip the ladders readily on account of their counterbalanced condition. A hand-wheel m^3 is shown in Fig. 3 to rotate the turntable in the ring f in the usual manner.

The extension-ladder as shown in Figs. 10^a and 10^b is made with inner rails D and outer rails D' and spacing-blocks D^2 between the two, which rest upon the rails C . Bolts or rivets h (Fig. 15) secure the parts D , D' and D^2 together, and the rail D' is braced by truss-rods D^7 .

The means for switching or guiding the car from the main to the extension-ladder in Figs. 11 to 15 inclusive, shoes or lugs i being projected from the ends of the rails D into the groove c' . The inner sides of the rails D are formed with grooves d' corresponding to the grooves c' in the rails C , but lying closer together, and, when the ladders are horizontal, at a higher level, as shown in Fig. 13. The outer rail D' of the extension-ladder also has hooks d^3 upon its lower edge adapted to engage the lower edge of the main ladder-rail C , which is especially strengthened at its upper end by a grooved block k' which the hooks engage when the extension-ladder is fully projected, as shown in Fig. 6. At such time, locking-bolts d^2 may be extended through the rails C , D and D' , to form a rigid joint for the two ladders.

It will be understood that the upper end of the main ladder and the lower end of the extension-ladder are, in practice, sheathed in sheet-metal which gives such bolts a rigid fulcrum to hold the parts together.

The means to elevate the extension-ladder are shown in Figs. 3 and 6, consisting of power-drums l and l' of different sizes operated by any desired power. A bracket m is extended downwardly upon the turntable to sustain the rack-bar or suitable pusher to engage the foot of the main ladder and swing it into any desired position. Such swinging movement is easily effected by hand gearing where the weight of the ladder is perfectly balanced, as is possible with the means shown herein, thus avoiding the use of ropes, drums, and a connection to a source of power, with liability to derangement. A tube m' is attached to the truss-rod b^2 and

swiveled into the bracket m , and a pulley n is journaled in the side of the tube so as to guide any rope which comes downward from the turntable toward the hoisting-drums l , l' .

A group of pulleys n' (see Fig. 8) are journaled upon the turntable close to the center of the ladder, and guide any rope from the hoisting-drums toward the under sides of the ladders. Figs. 6, 8 and 9 show the pulleys n' adjacent the lower ends of the ladder-rails C where they join the frame C' , and Fig. 6 shows a rope o extended over the pulleys and over a pulley p to an eye q . The pulley p is journaled upon the upper end of the main ladder, and the eye q is attached to a rung d of the extension-ladder, so that the winding of the rope by one of the drums l , l' operates to elevate the extension-ladder. A rope o' is also shown extended over one of the pulleys n' in Fig. 6 to a pulley p' upon the upper end of the extension-ladder, and thence to a hook r upon the upper end of the car, whose bearing-rolls or wheels s are shown resting upon the rails D' in Figs. 6, with pawls t' fitted to ratchet-teeth on the rolls. The rope o' is connected with the eye q by a detachable link r' , and a rope o^2 is extended from such link over one of the pulleys n' to the opposite side of the drum carrying the rope o ; so that the rotation of the said drum in opposite directions moves the car forward and backward upon the ladders, which is necessary if the ladders be nearly horizontal. When elevated, the car descends by its own weight and needs merely the hoisting-rope o' , the pawls t' then engaging the ratchet in the rolls s .

The construction of the car is fully shown in Figs. 11 and 12, with the rear end deeper than the front end and provided with a step-bar s' , by which anyone ascending the ladder can step into the car over its rear end. Partitions s^2 are extended across the inside of the car at uniform distances, which can be used as steps when it is necessary to pass over the car in ascending the ladder. Such partitions are provided with holes s^7 and s^8 for the passage of hose, and perform a different function from mere rungs or steps, in forming compartments which serve to hold articles or persons in position when the car is in motion. The partitions thus serve several functions. Hand-rails t are shown extended around the top of the car excepting at the front end, which afford a support to those who are riding in or passing over the car. Bearing-plates s^4 upon the sides of the car, adjacent to the rolls s , carry guide-ribs s^5 to fit the edges of the ladder-rails. The bearing-plates are on a line with the bottoms of the rolls to sustain the car if needful. The guide-ribs fit upon the inner sides of the rails C , as shown in Fig. 14, where one of

the rolls is omitted to expose the bearing-plate and guide-rib, and the guide-ribs fit upon the outsides of the ladder-rails D, thus moving in a straight line upon the two ladders. A sufficient clearance is provided between the rails C and D, to admit the guide-ribs s^5 , and the rails C and D are held with such interspace open where the car moves from one to the other, by a suitable adjustment of the shoes i in the grooves c' of the rails C, as is shown in Figs. 12 and 15. The lower edges of the car, as shown in Figs. 13 and 14, move between the rails, and latch-bars u are fitted to guides u' upon the bottom of the car, which hold them in line with the grooves c' or d' in the rails upon which the car is riding. The latches are pressed normally outward by springs v shown in Fig. 12, and are thus adapted to fit the grooves c' of the rails C, as shown in Fig. 14, or to be pressed inward to engage the grooves d' of the rails D. Means is thus provided for crowding the latch-bars inwardly when the car moves from the main ladder to the extension-ladder, in whatever position the extension-ladder may be located; such means being shown in Figs. 13 and 15, and consisting of trough-shaped metal channels d^4 attached to the inner sides of the shoes i and sloped not only inwardly as shown in Fig. 15, but upwardly as shown in Fig. 11, so as to carry the end of the sliding latch-bar from the groove c' to the groove d' . The shoes are formed as part of a metal sheathing v' attached to the lower ends of the rails D, as shown in Fig. 15, and thus carry the twister channels d^4 to any position where the extension-ladder may be moved upon the main ladder.

Fig. 11 shows the forward bearing-rolls S upon the rescue-car resting upon the rails D, while the rear bearing-rolls s are resting upon the rail C, the car having partially moved from one ladder to the other.

Fig. 11 shows pockets or sockets w formed in the lower edge of the rails D, and detents w' hinged by a shaft v upon the inner sides of the rails C and provided with spring w^2 to press them into the pockets. The detents thus operate automatically, as the extension-ladder is raised, to hold both of the rails D in their projected position, and a cord w^3 is shown attached to one detent which may be extended to any required point, as upon the turntable, to release the detents when it is desired to lower the extension-ladder. The front partition s^2 in the car is formed with two holes s^3 to receive pins d^2 upon the lower end of an emergency ladder D^3 .

While the car is merely carrying the ladder upward, its rails rest upon a support furnished by the upper end-piece of the car, as shown in Figs. 11 and 12, and any cross-bar at that end of the car may serve as such support. Fig. 1 shows the car thus sup-

porting the emergency ladder and operating, when the car is pushed upward, to project such ladder beyond the top of the extension-ladder itself. The upper end of the emergency ladder is preferably provided, as shown in Figs. 16 and 17, with a hinged and elastically-supported guide frame having side-bars E hinged upon one of the rungs E' of the emergency ladder, and projected upward beyond the same. A spring E² is applied to the fulcrum of the frame to press it normally outward, that is, toward any wall over which the ladder is moving. A stop E³ limits such outward movement to the degree shown in Fig. 17. Such frame is provided with a guide-wheel F and the arms of carriage are bowed outwardly adjacent to the guide-wheel so as to rest upon the wall of any building when the emergency ladder is pushed upwardly; the wheels acting to guide the frame over sills, lintels and other projections upon the front of a building, while the bowed arms of the frame serve to bridge across any window or other openings in a wall. The wheel F has a soft tire to cling to any surface. The spring E² operates, when the frame rests upon or moves over the wall of a building, to hold the top of the emergency ladder away from such wall, and to permit the hinged carriage to swing away from the wall without any resistance from the ladder, when jolted by passing over irregularities of its surface.

A yoke G is shown hinged to turn between the side-bars of the frame and formed with a hook or gaff G' to engage the top of a wall or fence or a window-sill H, as shown upon the wall I in Fig. 17. The hub of the yoke is shown formed with arms J and J' to which cords k^2 and k^3 are attached and are, in practice, extended to the bottom rung of the emergency ladder to which they are loosely secured. The pulling of the cord k^3 serves to draw the yoke with the hook in between the side-bars of the frame, as shown in the dotted lines G in Fig. 17, thus enabling it to clear any objects over which the frame moves. The cords enable the operator to throw the yoke downward and to engage the hook G' with any object upon which it can overlap, and then detach it therefrom.

The emergency ladder, as shown in Fig. 11, is provided with lugs d^5 near the foot of its side-rails, by which lugs it can, if necessary, be supported upon the rungs of another ladder when removed from the rescue-car.

Fig. 5 shows the underslung platform K having ears L adapted to hook upon one of the rungs D^4 of the extension-ladder, and held in a horizontal position by chains L' looped over another rung D^5 of the same ladder.

Fig. 7 shows upon a larger scale the rails

D of the extension-ladder with the ears L hooked upon the rung D⁴, and the chains L' extended to staples L² at the outer end of the platform. In Fig. 5 the platform is shown adjusted opposite a window-sill H' upon the front of a building I', so that persons who could not reach the ladder from such window may readily walk across the undersling to the ladder, where the removal of a rung D⁶ would permit them to readily pass to its outer side.

Means for removing a rung is shown in Figs. 10^a, 10^b and 10^c, in the bolts h² which are extended through the rails D, D', and space-blocks D² of the extension-ladder and formed with dovetailed heads h³ upon the inner sides of the rails D, to which the ends of such detachable rungs are removably fitted. The detachable rung, the main body e⁵ of which is made of wood, is shown with metallic sockets e⁶ upon its ends having dovetailed notches e³ adapted to fit the bolt-heads h³. To make such a rung unbreakable, a wire e⁴ is extended through the broadened bases of the notches at both ends of the rung and wound over and over longitudinally upon the body of the rung, as shown at e⁴ in Fig. 10^a, thus holding the metallic heads securely upon the rung and supporting the rung against any accidental breakage. Blocks or stops c⁵ are shown in Fig. 10^b at one side of the bolt-heads h³, to support the rungs when placed upon the bolt-heads, but any other means may be used for that purpose. The detachable rungs may also be made of solid metal. Such detachable rungs may be provided upon either of the ladders at any desired point and greatly facilitate the use of the apparatus with the car.

The permanent rungs of the extension-ladder should extend through both the inner and outer rails of the same to properly unite them, and give such strength to the structure that detachable rungs may be used at various points without impairing the rigidity of the ladder. Telescoping channel-bars are projected from the outer or rear end of the metal plate C' and are united by cross-ties so as to form frames adapted to slide one within the other. Figs. 18 to 20 show these frames, and the special means provided for adjusting them upon one another to vary the effect of the counterweight upon the ladders. The two largest channels C⁵ are attached rigidly and permanently to the ends of the S-shaped metal plates C', as shown in Figs. 8 and 9; channels C⁴ connected by ties c⁴ slide in the channels C⁵, which are connected by ties c⁵, and channels C³ are connected together to slide in the channels C⁴, as shown in Figs. 18 to 20, to carry the counterweight and to support an operator who may adjust the telescoping parts upon one another at all

times in the operation of the ladders. A cross-bearing 1 is fitted between the channels C³ at their forward ends, and a hand-wheel mounted upon an upright shaft 2 therein, carries a pinion 3. A rack 4 is secured to the tie-bars c⁴ of the channels C⁴ and the pinion meshes with such rack, as shown in Fig. 18, so that when the hand-wheel is turned the frame having channels C³ may slide in and out of the channels C⁴. One of the tie-bars c⁴ connects the lower flanges of the channels C⁴ (see Fig. 20) and carries a bearing for a shaft 5 and pinion 6, and a rack 7 meshing with such pinion is attached to the cross-tie c⁵, so that the pinion 6 may move the channels C⁴ in the channels C⁵. A plate c⁶ preferably connects the upper edges of the channels C³, to support a firm seat for an operator within reach of the hand-wheel upon the shaft 2, a foot-rest 8 being projected inward from each of the channels C³ adjacent to the pinion 2 to support the operator in turning the pinion. The counterweight C² is shown upon such plate in Fig. 19. When the frame having the channel C³ is moved wholly into the channel-bars C⁴ it brings the hand-wheels near one another so that the operator can reach the hand-wheel upon the shaft 5, and thus move the frame C⁴ inward or outward as desired.

Fig. 3 shows only the channel C⁵ which is bolted permanently to the pivot-frame C', the telescoping frames being wholly retracted when the truck carrying the ladders is in transportation, for the reason that the weight of the main ladder is supported upon posts a⁶ and a⁷ at such time, and because the extension-ladder whose rails D' show in Fig. 3, would be wholly retracted, as shown in that figure, and thus partly counterbalance the weight of the main ladder.

Fig. 9 shows the rails C of the main ladder inclined downwardly from a horizontal line, and the proportions of the pivot-frames C' may, if desired, be made as in Fig. 9 so that the main ladder may be inclined below the horizontal line in any desired degree so that the ladders may reach points otherwise inaccessible below the level of the turntable.

It will be understood that the ropes o, o² and o³ may be wound upon the drum so as to extend therefrom to just the desired distance to reach their points of attachment and operate the extension-ladder and the rescue-car as desired, such distance being determined by the position of the parts when the ropes are thus attached and the ropes being "paid out" or "wound in", as may be required, whenever adjustment of the ladders is changed.

Instead of using separate ropes to elevate the extension-ladder and actuate the

car, the same rope may be first used to raise the extension-ladder to the desired point and then detached from the eye q and extended over the pulley p' to the hook r upon the car. The detachable link r' permits of the convenient detachment and attachment of the rope in such cases.

No claim is made herein to a truck having a turntable and supporting ring with 10 openings in the side through which a ladder can be swung from a vertical to a horizontal position, as such a construction is shown and claimed in the application No. 728,722 filed October 28, 1912 by B. F. Carpenter 15 and W. McMane. The present construction differs from that in the said application, by the connection of the counterweight and the main ladder by an S-shaped metallic frame which sustains the counterweight 20 opposite the center of gravity of the combined ladders, while it also enables the ladder to move from a vertical to a horizontal position without intersecting the edge of the turntable ring, and thus avoiding the 25 formation of any gap in such ring. The continuous ring is obviously stronger and affords a better support than one having a gap for the heavily loaded turntable. In the said application, a rack-bar or pusher 30 is shown extended from a pinion to the foot of the ladder for inclining and moving the same, and the rack-bar f' is shown herein connected to the rear end of the S-frame C' for the same purpose, but I have constructed 35 the connection with an index-finger f^3 upon the end of the cross-bar f^2 (see Fig. 3) and connected the end of the rack-bar with the cross-bar by a loose slot and bolt connection shown at f^4 in Figs. 21 and 22, 40 to show the operator upon the telescoping frames whether the counterweight overbalances or underbalances the weight of the ladder. If the counterweight underbalances the weight of the ladder the frames C' will 45 pull upon the rack-bar and thus slightly rotate the cross-bar f^2 , and turn the index-finger to the left and elevate it above the top of the frame C' , as shown in Fig. 3. If the counterweight overbalances the ladder, the frame C' will push upon the rack-bar and turn the cross-bar in the opposite direction, thus throwing the index forward and below the upper edge of the frame C' . The index finger thus indicates clearly to 55 the eye of the operator the direction in which the ladder and car are unbalanced, so that the operator can at once shift the counterweight to restore such balance. The index-finger has a knob upon its upper end 60 which when elevated above the edge of the frame C' shows the operator that the ladder is underbalanced, and that the counterweight should be moved outwardly, as indicated by the word "Out" on the frame C' . 65 If the knob on the index-finger disappears

beneath the edge of the frame C' , it shows the operator that the ladder is overbalanced and that the counterweight should be moved inwardly, as indicated by the word "In" on the frame C' . The ladder can be thus kept 70 balanced so perfectly as to make the labor very slight in tipping it by the hand-wheel 7^3 , which enables the operator to vary the position of the ladder and car with the utmost facility.

When it is desirable or necessary to operate the car upon the extension-ladder when its lower rungs are below the sheaves n' , as shown in Fig. 3, the link r' upon the rope o' is detached from the car and led between such rungs d of the extension-ladder as will permit it to pass in a direct line as nearly as possible to the pulley p' . Such condition exists when the front of the extension-ladder is retracted beyond the foot of the main-ladder, as is indicated in Figs. 3 and 4 of the drawing.

Certain attachments may be made to the extension-ladder to diminish the friction when moving over the main ladder rails C , 90 such attachments consisting of rolls k^4 journaled one upon the foot of each of the rails D and extending beneath the lower edge of the rails C , and rolls k^5 journaled between the rails D and D' intermediate to the spacing-blocks D^2 to bear upon the upper side of the rails C . Such rolls are especially useful near the lower end of the extension-ladder as the strain upon the bearing parts of the two ladders increases as the extension-ladder is drawn upwardly.

Fig. 6 represents the foot of the extension-ladder raised to the highest point upon the main ladder, and the rolls k^4 and the hooks d^2 coöperate together in holding the foot of the extension-ladder firmly to the top of the main ladder. In Fig. 4 where the rails D and D' of the extension-ladder are shown, the blocks D^2 are shown disposed between such rails in line with the rungs d so that 105 the rungs may be extended through the same, which greatly strengthens the connection. Such blocks may be applied to each alternate rung or at any distances apart that are found desirable, and the auxiliary bearing-rolls d^5 may be made upon the rungs intermediate to those which penetrate the blocks D^2 . The rolls k^5 are shown only near the foot of the main ladder in Figs. 6 and 110 15, but may be applied to the extension-ladder at any point of its length.

From the above description it will be seen that each element of the structure contributes to the most comprehensive and efficient use of the car, and permits the tipping 125 of the ladder, and its rotation with the turntable by manual agency which can operate with greater promptness and certainty than any operated by power, as the operator is able to see what is required, and to act ac-

cordingly; while mere mechanism has no such capacity. The operator standing upon the turntable in control of the wheels ⁷² and ^m³ is thus able to extend the ladder in any direction from a central point, and to elevate it to any position from a horizontal to a vertical position; thus controlling the propelling of the car to any point in a hemisphere above the center of the ladder's movement.

10 Having thus set forth the nature of the invention what is claimed herein is:

1. A rescue apparatus having a truck with a ladder pivoted thereon, a car movable on the ladder, means to propel and retract the car, means upon the truck for extending the ladder in any direction from a central point and elevating it to any position from a horizontal to a vertical position, and means to balance the car and ladder in any position.

20 2. A rescue apparatus having a truck with a turntable thereon, a ladder pivoted upon the turntable with a car and means to propel and retract it upon the ladder, means for extending the ladder in any direction from the center of the turntable, and means for elevating it upon the truck to any position from a horizontal to a vertical position whereby the car may be propelled to any point in a hemisphere above the center of the turntable, and means to balance the car and ladder in any position.

30 3. A rescue apparatus having a truck, a ladder pivoted thereon, with a car and means to propel and retract it upon the ladder, means for extending the ladder in any direction from a central point upon the truck, means for elevating the ladder upon the truck to any position from a horizontal to a vertical position, and means adjustable by an operator for balancing the ladder and car in any adjustment thereof.

40 4. A rescue apparatus having a truck with a ladder pivoted thereon, a car having rolls to rest upon the rails of the ladder and means to engage the inner sides of the rails to hold the car thereon, means to elevate the ladder at any angle, means to propel and retract the car upon the ladder, and the interior of the car provided with partitions forming compartments therein to retain objects or persons in the car when the ladder is elevated.

50 5. A rescue apparatus having a truck with a ladder pivoted thereon, a car having rolls to rest upon the rails of the ladder and means to engage the inner sides of the rails to hold the car thereon, means to elevate the ladder at any angle, a metallic step-bar projected from the lower end of the car, partitions within the car forming compartments to retain articles or persons in place when the ladder is elevated and serving as steps whereby an operator may pass safely over the car in ascending the ladder, and hand-

rails upon the sides of the car to assist such operator.

6. A rescue apparatus having a truck with ladder pivoted thereon, a car having rolls to rest upon the rails of the ladder and means to engage the inner sides of the rails to hold the car thereon, partitions, forming compartments to hold objects or persons, disposed to serve as steps for the passage of an operator, the front partition having holes to receive the foot of a ladder and the front end of the car having a support for such ladder, and an emergency ladder having the feet of its rails provided with pins fitted loosely to the said holes, and the rails resting upon the said support, and the ladder having a hinged guide-frame at the upper end adapted to move over any contiguous surface.

7. A rescue apparatus having a truck with ladder pivoted thereon, a car having rolls to rest upon the rails of the ladder and means to engage the inner sides of the rails to hold the car thereon, partitions, forming compartments to hold objects or persons, disposed to serve as steps for the passage of an operator, the front partition having holes to receive the foot of a ladder and the front end of the car having a support for such ladder, and an emergency ladder having feet fitted to said holes and having a guide-frame with side-bars pivoted near its upper end, and the guide-frame having a guide-wheel at its upper end with cushion tire thereon, and the side-bars bowed outwardly from the ladder adjacent such wheel, and a spring upon the ladder adapted to press the guide-frame normally outward therefrom.

8. A rescue apparatus having a truck provided with a turntable and a main-ladder pivoted thereon, an extension ladder having rails fitted within the rails of the main-ladder with a clearance forming a small interspace, a car having rolls adapted to travel upon the rails of both the ladders, and having guide-ribs adapted to fit inside the rails of the main-ladder and to pass through such interspace to fit outside the rails of the extension-ladder, and thus guide the car laterally upon both of the ladders.

9. A rescue apparatus having a truck provided with a turntable and a main-ladder pivoted thereon, an extension-ladder having rails fitted within the rails of the main-ladder with a clearance forming a small interspace, a car having rolls adapted to travel upon the rails of both the ladders, and having bearing-plates projected from the car over both rails and each plate provided intermediate its edges with a guide-rib adapted to fit and move in the said space outside the rails of the extension-ladder and inside the rails of the main-ladder.

10. A rescue apparatus having a truck

provided with a turntable and a main-ladder pivoted thereon, an extension-ladder having rails fitted within the rails of the main-ladder with a clearance forming a 5 small interspace, a car having rolls adapted to travel upon the rails of both the ladders and having guide-ribs adapted to fit inside the rails of the main-ladder and outside the rails of the extension-ladder, all of the said 10 rails having grooves upon their inner sides, and yielding latches upon the car adapted to engage the said grooves and retain the car on the ladders.

11. A rescue apparatus having a truck 15 provided with a turntable and a main-ladder pivoted thereon, an extension-ladder having rails fitted within the rails of the main-ladder with a clearance forming a small interspace, a car having rolls adapted to travel 20 upon the rails of both the ladders and having guide-ribs adapted to fit inside the rails of the main-ladder and outside the rails of the extension-ladder, all of the said rails having grooves upon their inner sides, the 25 grooves upon the extension-ladder rails being sloped at the lower ends of such rails to coincide with the grooves in the main-ladder rails, and spring-latches upon the car adapted to engage the grooves in the main-ladder 30 rails and to yield inwardly when moved into the grooves of the extension-ladder rails.

12. A rescue apparatus having a truck provided with a turntable and a main-ladder pivoted thereon, an extension-ladder having 35 rails fitted within the rails of the main-ladder with a clearance forming a small interspace, a car having rolls adapted to travel upon the rails of both the ladders and having guide-ribs adapted to fit inside the rails 40 of the main-ladder and outside the rails of the extension-ladder, all of the said rails having grooves upon their inner sides, shoes upon the foot of the extension-ladder rails fitted to the grooves in the main-ladder rails, 45 twisted channels connecting the grooves in both ladders upon the inner sides of such shoes, and spring-latches upon the car adapted to engage the grooves in the main-ladder rails and to be guided by the channels into 50 the grooves of the extension-ladder rails.

13. A rescue apparatus having a truck

provided with a turntable having an opening in the center, pivot-bearings upon the turntable at the sides of the opening, an S-shaped frame having a body pivoted upon 55 the said bearings, and a ladder having its foot attached to one end, and the opposite end extended beyond the edge of the turntable, and provided with a counterweight, a car movable upon the ladder, means to propel and retract the car upon the ladder, and means operated by hand for rotating the turntable and tipping the ladder in any position from the horizontal to the vertical, and means for adjusting the counterweight 60 by hand whereby the car may be balanced when moved to any point in a hemisphere above the center of the ladder's movement.

14. A rescue apparatus having a truck provided with a turntable having an opening in the center, pivot-bearings upon the turntable at the sides of the opening, an S-shaped frame having a body pivoted upon 70 the said bearings, and a ladder having its foot attached to one end, and the opposite 75 end extended beyond the edge of the turntable and provided with a counterweight, a car movable upon the ladder, means to propel and retract the car upon the ladder, a pusher for tipping the ladder, an index actuated by the pusher indicating the direction in which the ladder and car are balanced, and means for adjusting the counterweight to restore such balance.

15. A rescue apparatus having a truck 85 with turntable thereon, a ladder pivoted upon the turntable, a car with means to raise and lower it upon the ladder, an underslung platform with means for supporting it detachably from the rungs of the ladder, 90 and the ladder having detachable rungs to facilitate movement from the underslung platform to the outer side of the ladder and the car.

In testimony whereof I have hereunto set 95 my hand in the presence of two subscribing witnesses.

BENJAMIN F. CARPENTER.
